COSMETIC CONTAINER UNIT

Pearl L. Schluttig, Washington, D. C.

Application September 25, 1951, Serial No. 16,739

Term of patent 14 years

(Cl. D86—10)

To all whom it may concern:

Be it known that I, Pearl L. Schluttig, a citizen of the United States, residing at Washington, in the District of Columbia, have invented a new, original, and ornamental Design for a Cosmetic Container Unit, of which the following is a specification, reference being had to the accompanying drawing, forming a part hereof.

The dominant features of my design reside in the portions shown in full lines.

I claim:

The ornamental design for a cosmetic container unit, as shown and described.

PEARL L. SCHLUTTIG.
